WELDING GUN FOR SHIELDED ARC WELDING

Wilhelm Dinse, 2 Hamburg 70, Konigsreihe 12,
Hamburg, Germany

Filed June 1, 1972, Ser. No. 258,919

Term of patent 14 years

Int. Cl. D8—05

U.S. Cl. D8—30

FIG 1

FIG 2

FIG 3

FIG 4

FIG 5

FIG 6

FIG 7

FIG. 1 is a perspective view of the welding gun for shielded arc welding as viewed from the rear and one side thereof.

FIG. 2 is another perspective view thereof as viewed from the front and one side thereof.

FIG. 3 is an elevation view of one side thereof. The other side appears identically, in mirror image, to FIG. 3.

FIG. 4 is a top plan view thereof.

FIG. 5 is a front elevation view thereof.

FIG. 6 is a rear elevation view thereof.

FIG. 7 is a bottom plan view thereof.

I claim:

The ornamental design for a welding gun for shielded arc welding, as shown and described.
